UNITED STATES PATENT OFFICE.

FRANK M. MAHAN, OF CHICAGO, ILLINOIS.

DESIGN FOR A CAMPAIGN-BADGE.

SPECIFICATION forming part of Design No. 31,573, dated October 3, 1899.

Application filed May 5, 1899. Serial No. 715,742. Term of patent 7 years.

To all whom it may concern:

Be it known that I, FRANK M. MAHAN, a citizen of the United States of America, residing at Chicago, county of Cook, and State of Illinois, have invented and produced a new and original Design for Campaign - Badges, of which the following is a specification.

Referring to the accompanying drawings, Figure 1 is a face view of my badge, and Fig. 2 is a top edge view of the same.

As shown in the drawings, the leading or essential features of my design comprise a substantially triangular shield-shaped figure, two parts of the surface thereof being of contrasting or different appearance or color, as indicated at A and B. The line of division between the two surface parts is shown as vertical and substantially in the center of the shield, dividing it into two halves. In the upper part of the shield are three stars C, D,

and E. These stars also, as indicated, are of contrasting or different appearance or color. Between the stars are blank spaces for the reception of numbers, words, or other indicating characters. A suitable blank space F ²⁵ is provided below the stars and spaces above referred to for other words or characters, and below the space F is still another blank space G. In the badge illustrated, below the blank spaces, are series of parallel vertical lines or ³⁰ score-marks, (indicated at a and b.)

Having thus described my invention, what I claim as new, and desire to secure by Letters Patent, is—

The design for a campaign-badge, substantially as shown and described.

FRANK M. MAHAN.
